(57) **CLAIM**

The ornamental design for a compression wrap insert, as shown and described.

DESCRIPTION

FIG. 1 is a top perspective view of a compression wrap insert, showing my new design.

FIG. 2 is a top view thereof.

FIG. 3 is a front view thereof.

FIG. 4 is a bottom plan view thereof.

FIG. 5 is a right side view thereof.

FIG. 6 is a left side view thereof.

FIG. 7 is a perspective view of the insert in an inverted position in a compression wrap, with the broken line showing of the limb and compression wrap being for illustrative purposes only and forming no part of the claimed design; and,

FIG. 8 is a back view thereof.
